LOCOMOTIVE BOILER STRUCTURE

John A. Pilcher, Roanoke, Va.

Application October 20, 1930. Serial No. 490,064

3 Claims. (Cl. 122—493)

My invention relates to the bracing of boiler sheets in structures where the boiler walls form relatively angular corners, a familiar example of which is found in railway locomotive boilers where

5 the roof sheet meets the backhead and front flue sheets and braces extend diagonally across the corner to hold the sheets against distortion.

Boiler corner braces are usually attached to the roof or wrapper sheet and the boiler head by 10 means of separate brackets, the head brackets being T-shaped and secured in place by rivets in pairs of parallel rows. A multiplicity of irregularly spaced rivet holes must accordingly be bored in the head, which obviously weaken the boiler 15 and crowd various boiler fittings usually mounted on the boiler back head.

The general object of my invention is to provide a simple and effective means of attaching the braces to the boiler sheets, and at the same 20 time leaving ample room for necessary washout plugs, throttle rod openings, gauge cock, dry pipe and other openings without interfering with the braces or rivets.

Other objects and applications of my invention 25 as well as details of construction whereby my invention may be put in practice will appear more fully hereinafter when taken in connection with the accompanying drawings, wherein:

Figure 1 is an end view of the rear half of 30 a boiler embodying my invention.

Figure 2 is a vertical transverse section through the same taken approximately on the line 2—2 of Figure 3.

Figure 3 is a vertical longitudinal section 35 through the center of the upper portion of the fire box and adjacent boiler sheets.

Figure 4 is a horizontal section taken approximately on the line 4—4 of Figures 1 and 2.

Figure 5 is a vertical transverse section through 40 the upper portion of the fire box and adjacent boiler sheets embodying a modified form of my invention.

Figure 6 is a vertical longitudinal section through the same structure.

45 Figure 7 is a detail illustrating another modification of my invention.

Figure 8 is a vertical section through a boiler front head upper member comprising a single casting.

50 In the construction shown in Figures 1, 2, 3 and 4, I illustrate a one piece casting forming the upper portion of a boiler backhead and comprising a body wall 35 with an inturned flange 36 at its upper end adapted to be riveted at 37 to 55 the boiler roof sheet 38. The lower edge of wall

35 may be welded to the upper edge of the backhead sheet proper 39, as indicated at n, or these backhead elements may be overlapped and riveted together.

The body wall 35 is reinforced by suitable substantially radially disposed flanges 40 which merge at their upper ends with flange 36 and provide anchorage for the brace rods 41 replacing the usual T irons for this purpose. Rods 41 have jaws 42 on their ends arranged to receive the flanges 40 between them. The rods are secured by the usual pins 43. The roof sheet and back head are further braced from the fire box crown sheet 38a and door sheet 39a by stay bolts 44 and 45. Perforated bosses A, B, C and D for washout plugs, throttle rod, and other equipment may be suitably positioned on the surface of the head without the necessity of avoiding the multiplicity of rivets heretofore applied to the head.

In this arrangement one brace is provided for 75 each flange 40 and this brace is attached near the lower end of the flange so that the load from the internal pressure bearing against the top portion of the casting will be resisted by the braces 41 and by the rivets 37 tieing the flange 80 36 to the roof sheet 38. This arrangement divides the load from the internal pressure between the braces 41 and the roof sheet 38. The flanges 40 are sufficiently strong to carry the load between the two points of support and are spaced 85 close enough to prevent the upper portion of the backhead from bending or breaking. They eliminate the necessity of the usual outside sheet and reinforcing brackets at this portion of the backhead and eliminate the usual rivets required 90 for attaching the sheet to the brackets. Pads 40a are provided on the outer face of wall 35 so that workmen drilling through the wall can avoid ribs 40.

Figures 5 and 6 illustrate a similar backhead 95 casting 46 secured to the back sheet 9 and provided with transverse flanges 47. The boiler structure differs from that shown in Figures 1 to 4 in having a plurality of braces 48 secured to each flange 47, thus distributing the pressure on 100 the upper portion of the head over a larger part of the roof sheet.

The use of the single brace for each flange, as shown in Figures 1 to 4, reduces the weight of the material in the braces by distributing a 105 large portion of the pressure load directly to the roof sheet through the flange 36. The design with the plurality of braces secured to each flange, as shown in Figures 5 and 6, reduces the size needed for each individual brace but provides a greater 110

total of brace area because less load is taken directly from the upper end of the casting to the roof sheet. The flanges need not be so strong where the multiple braces are used as the points of support are closer together. The preferred design in any installation would be governed by the special demands and conditions of the particular boiler design.

Figure 7 shows a modification of the structures, 10 illustrated in Figures 1 to 6, in which the back-head sheet 49 overlaps the lower portion of an upper backhead casting 50 and rivets 51 secure the two head portions together.

Although Figures 1 to 7, inclusive, illustrate 15 backhead structures, it will be understood that the same elements of design may be embodied in front flue or tube sheet structures.

As an example, Figure 8 shows a casting 52 having a flange 53 for attachment to the boiler 20 roof sheet 54 and preferably having the dry pipe attaching member 55 integral with the upright wall. Ribs 56 provide for attachment of corner braces.

Various other modifications in the details of 25 my invention may be made without departing from the spirit thereof and I contemplate the exclusive use of those variations which come within the scope of my claims.

I claim:

30 1. A new article of manufacture constituting a locomotive boiler head upper member and con-

sisting of a cast wall portion provided with an integral inwardly turned top flange for attachment to the boiler roof sheet, integral outstanding ribs extending from the inner edge of said flange to the lower edge of said wall, and elements near the lower extremities of said ribs for the attachment of brace rods.

2. In a locomotive boiler, a boiler roof sheet, a boiler head sheet extending at an angle thereto, the upper part of said head sheet comprising an inherently form-sustaining member having a flange for attachment to said roof sheet and having bracing ribs merging with said flange, and brace rods extending from said roof sheet to portions of said ribs spaced from said flange and cooperating with said ribs and said flange to transfer head pressures directly to said roof sheet. 80 85 90

3. In a locomotive boiler, a roof sheet, a back head, a fire box rear sheet, the lower portion of said back head being braced from said rear sheet, and the upper portion thereof above said rear sheet comprising an inherently rigid member having an integral flange at the top directly connected with said roof sheet and integral outstanding ribs extending from said flange to the lower edge of said member, and brace rods extending from said roof sheet to the lower portion of said ribs, said flange, ribs, and rods serving to transmit all pressures on said upper portion directly to said roof sheet. 95 100 105
